(57) **CLAIM**

The ornamental design for a vehicle fender, as shown and described.

DESCRIPTION

FIG. 1 is a front and left side perspective view of a vehicle fender showing our new design; the mirror images of the vehicle fender is claimed, but not shown; FIG. 2 is a front elevation view of the vehicle fender of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle fender that form no part of the claimed design.

1 Claim, 7 Drawing Sheets
